UNITED STATES PATENT OFFICE.

HELEN C. GAMBLE, OF NEW YORK, N. Y.

COLLAPSIBLE HAT BAG.

Application filed November 24, 1921. Serial No. 517,420.

This invention relates to collapsible bags.

More particularly, the invention relates to collapsible bags for hats and similar fragile objects. An object of the invention is to provide a bag for hats and the like which when not in use may be collapsed to greatly reduced over-all dimensions and with minimum removal of the parts of the bag.

A further feature of the invention is to provide a construction of fabric and arrangement of the stiffening parts, usually of metal or the like, whereby convenience of access to the one or more compartments of the bag is facilitated while the bag is resting on any suitable support or while being suspended.

With the above objects in view, a preferred form of my invention comprises fabric usually of circular sectional contour and formed to provide a single compartment by the provision of laterally disposed stiffening means removably secured in position by relative movement of one portion to another portion. In other preferred forms of the invention as in the multi-compartment forms, the bottom of the fabric is stiffened by a hoop of the above form of stiffening means and also to provide a partition between the succeeding upwardly disposed compartments, and access afforded to the respective compartments by the provision of an opening formed in the fabric at one lateral side of the fabric. Preferably such multi-compartment form of my invention is of the suspended type.

When it is desired to collapse the bag the material of the bag is dropped in alignment and by grasping the opposite diametrical portions of the bag and twisting through 180 degrees are of movement and folding the resulting two circular portions of reduced diameter one upon the other, whereupon the bag thus collapsed both in height as well as in diameter may be stored in an envelope or the like.

A further object of the invention is to provide a bag or envelope for receiving such collapsible bag when in collapsed position or for receiving other articles as may be desired.

Further features and objects of this invention will be more fully understood from the following description and the accompanying drawings, in which

Fig. 1 is a perspective view of a unitary compartment type of bag, partly broken away to show the joint of the metal stiffening means;

Fig. 1^a is a detail sectional elevation on line 1^a—1^a of Fig. 1;

Fig. 2 is a top perspective view of Fig. 1;

Fig. 3 is a perspective view showing the bag illustrated in Figs. 5 and 6 being twisted to collapse the same;

Fig. 4 is a perspective view of an envelope for storing the twisted and folded bag;

Fig. 5 is a perspective view of a modified form of my invention, in which the top of the bag is closed by snap fasteners;

Fig. 6 is a top plan view of the bag shown in Fig. 5, with the top opened;

Fig. 7 is a detail exploded view showing the terminal portions of the metal stiffening hoop and securing means;

Fig. 8 is a perspective view of a two-compartment bag embodying my invention, partly broken away;

Fig. 9 is a perspective view of the bag shown in Fig. 8, with the fabric of the partition removed, to show hidden parts;

Fig. 10 is a perspective view of a four-compartment bag embodying my invention; and

Fig. 11 is a perspective view of an envelope for storing the collapsed bag shown in Figs. 8 and 9.

Referring to Figs. 1 and 2, the form of my invention is of the single compartment form and is closed at its top by means of a draw string 12. The bottom 13 of the collapsible bag is preferably circular in contour and may be formed as is indicated in Fig. 1 of a circularly cut piece of material and secured by a seam to the fold 14 formed at the lower end of the material 15 serving as the outer side of the bag. The material 15 of the outer side of the bag is continued upwardly to form the top 16 and adjacent the uppermost end 17 the draw string 12 is located.

The material of the bag may be of any suitable fabric of ornamental design or otherwise to suit the particular purposes for the bag or the fancy of the purchaser.

To give a suitable configuration to the material of the bag, I provide the hoop 18 which may be of any desired length and secured in position by means of suitable detachable coupling means adjacent the respective ends of the hoop. In Figs. 1 and 7, I show a particular form of coupling means comprising the pair of spaced, headed lugs 19, 20, cooperating respectively with the pair of bayonet slots 21, 22, the large opening of each of such slots 21, 22, permitting the heads of the respective lugs 19, 20 to pass therethrough whereupon the ends of the hoop 18 are pulled to move the body portions of the headed lugs 19, 20 with-

in the restricted portions of the slots 21, 22, respectively, until the end face 23 rides over and is brought in contact with the unheaded lug 24, to lock the ends of the hoop 18 firmly to one another.

To collapse the bag, the ends of the hoop 18 are uncoupled by manually applying force to the end 23 of the hoop 18 in a direction transverse to the direction of length of the 10 stiffening hoop 18, to thereby spring the terminal portion 23 out of contact with the lug 24 and sliding the lugs 19, 20 in the slots 21, 22 respectively until the heads of the lugs 19, 20 can be passed through the larger openings 15 of the slots 21, 22, and then removing the hoop 18 from within the bag.

However, I prefer that the bag be collapsed with the hoop 18 positioned therein and for such purpose the hoop 18 is made 20 of resilient material, such as tempered steel and may be permanently secured to the material of the bag by straps of fabric or the like sewed to the material and bridging the hoop 18 at three or more locations about the periphery of the hoop. Also, the vertically extending strips 25, 25 may be employed of whalebone, celluloid or like relatively light resilient material and snapped to the fabric in any suitable manner and to resiliently hold 30 the side portion 15 of the material of the bag in position. As one form of such disconnectible connection for the vertically extending strips 25, 25, I illustrate in Figs. 1 and 1^a, snap fasteners 25^a, 25^a for snapping the vertically extending strips 25 respectively to the peripheral portion 15 of the material of the bag.

To collapse such form of bag, the bag is allowed to collapse vertically upon unsnapping the vertically extending strips 25, 25 and 40 by grasping the material of the bag the opposite diametrically disposed portions 26, 27 as indicated in Fig. 3, and twisting the hoop 18 together with the material of the bag until the configuration 8 approximately is formed, 45 thus forming generally two circular portions, each portion being of approximately one-half diameter, and thereupon one circular portion folded upon the other to form the resulting form indicated at 28 which may be stored in the envelope 29 of suitable fabric or the like. The inner dimension of the envelope 29 is illustrated to retain the twisted and folded bag in the form indicated at 28 in Fig. 4.

In the use of the bag shown in Figs. 1 and 55 2, as when a hat is placed therein, the bag may be suspended manually or by hanging the loops of the draw string 12 on a hook, or the like.

If desired, as is indicated in Figs. 5 and 6, 60 the top 30 of the bag may be provided with snap fasteners 31, the members of which snap fasteners 31 are respectively secured to the closure flaps of the top 30. The suspension ring 32 is secured to a closure flap of the top 30 and preferably closely adjacent to the free

edge of its closure flap. Upon closure of the snap fasteners 31 and grasping the ring 32, the bag is suspended and the material of the bag is held in distended position.

If desired, as is indicated in Figs. 6 and 9, 70 the flap 13^a may be sewed to the bottom 13 of the bag for holding the hat pins which may be stuck through the material of the flap 13^a.

In Figs. 8 and 9, is shown another modification of a two compartment type wherein the bottom and side and top correspond to the parts of the modifications shown in Figs. 1 and 2, and Figs. 5 and 6 respectively and like parts are designated by the same reference numbers. However, in this construction two hoops 18 are employed and located respectively at the upper margin of the lower and upper compartments respectively. The partition between the upper and lower compartments is provided by means of the fabric 33 sewed at its circularly extending side portion 34 to the side portion 15 of the material of the bag and provided with the draw string 35 for closing the partition 33. In this particular modification, the closure flap of the bag is closed by the series of snap fasteners 31 applied adjacent the free edge of the closure flap and upon closure of the closure flap, the bag is suspended in distended relation of its parts by means of the ring 32 secured to the closure flap at a location between the ends of the free edge of the closure flap; access into the bag, as indicated in Fig. 9, is attained upon unsnapping the snap fasteners 31, grasping the ring 32 and moving the closure flap. The flap 13^a is provided at the bottom 13 for holding hat pins and the like. The hoops 18 are of the construction as hereinabove described, and the side 15 of the fabric may be resiliently stiffened by means of the circularly spaced vertically extending strips 25.

The bag shown in Figs. 8 and 9 may be collapsed by allowing the material to drop, 110 the top in substantial vertical alignment with the bottom similarly as in the modifications hereinabove described, and thereafter twisted and folded to final collapsed form.

In the modification shown in Fig. 10, I 115 have illustrated a four compartment bag having the circular bottom 40 preferably stiffened by a hoop 18 enclosed at its circumference and partitions 41, 42, 43 of circularly cut fabric and stiffened at their respective circumference by means of the hoops 18. However, in this modification, the material forming the circularly extending side 44 is cut to provide a vertically extending lateral opening closed by the flap 45 which is preferably of a width greater than the opening at the side of the bag. The top 46 of the bag is provided with the ring 47 for suspending the bag in a cupboard or other permanent or transitory location for receiving and protect- 120 125 130

ing four or more hats or like fragile objects. The flap of the bag may be secured in closed position by snap fasteners or by tie strings or the like.

5 In Fig. 11, I have indicated a circular envelope 48 for receiving the vertically collapsed twisted and folded bag shown in Fig. 10, the method of collapsing, twisting and folding being the same as that shown in the 10 above described modifications. The envelope 48 is provided with the hand holds 49 for carrying or suspending the envelope. As is illustrated in Fig. 11, the envelope or bag 48 is wholly closed on one of its flat sides 15 and on the opposite flat side is closed at the bottom and open at an upper part to provide a semi-circular flap for closing the bag. The pair of coacting hand holds 49, 49 are respectively secured to the upper edge of the flap 20 and to the body of the bag, whereby upon grasping the hand-hold 49 secured to the arc-shaped flap jointly with the hand-hold 49 secured to the circular edge of the bag 48, the arc-shaped flap is automatically held in 25 closed position. Preferably, as is also illustrated in Fig. 11, the circular edge of the arc-shaped flap of the bag 48 is provided with a circularly extending flange strip. If desired, the bag 48 may be provided with the 30 removable stiffening members such as the members 25 referred to hereinabove in respect to Fig. 1.

From the above it will be observed that I have provided a collapsible bag formed of 35 inherently collapsible material serving as the major material of the bag and hoops or the like of resilient material which may be readily removed or retained in position and collapsed and folded to greatly reduced dimension. It 40 will be also observed as appears from the construction of my bag shown in Figs. 8 and 9, that the spaced, circularly or peripherally extending hoops 18 and the transversely extending stiffening strips 25 combinedly form 45 an extended stiffening means for the peripheral or band portion of the material of the bag and hold the same in distended position, which stiffening means when in position resist the collapsibility of the oppositely disposed circular sides of the bag in radial direction as in my issued Patent No. 1,207,533, dated December 5th, 1916. If desired, the hoop for retaining the shape of the various 50 forms of my collapsible bag may be as the construction shown in my United States Patent No. 1,207,533, dated December 5, 1916, but of flat material having one or more lugs on one of the mutually engaging portions of the hoop and a series of bayonet slots in the other 55 60 of the mutually engaging portions of the hoop similarly as in the construction of the hoop 18 as is indicated in Figs. 1 and 7 herein respectively.

Whereas I have described my invention by 65 reference to specific forms thereof, it will be

understood that many changes and modifications may be made without departing from the spirit of the invention, as defined by the appended claims.

I claim:

1. An envelope of the character described comprising a peripheral band and a circular side, said circular side being formed of non-self-sustaining material, a portion of the material of said circular side forming a closure flap having a free edge extending from a location adjacent said peripheral band to another location adjacent said peripheral band, stiffening means secured to said peripheral band, said stiffening means extending longitudinally and transversely relative to said peripheral band, and means for suspending said envelope in its closed and distended position, said means including an element secured to said closure flap between the ends of the free edge of said closure flap and a series of fasteners mounted adjacent the free edge of said closure flap.

2. An envelope of the character described formed of substantially self-collapsing material shaped to have a peripheral band and circular side portions attached to one another to form a substantially closed container, a portion of the material of one of said sides forming a closure flap and serving when opened to provide an opening to afford access into the bag, said closure flap having a free edge extending from a location adjacent said peripheral band to another location adjacent said peripheral band, stiffening means permanently secured to said peripheral band, said stiffening means extending longitudinally and transversely relative to said peripheral band, a series of fasteners adjacent the free edge of said closure flap for securing the free edge of said closure flap in its closed position and means for suspending said peripheral member and said circular members, said suspending means comprising an element secured to said closure flap of said one circular member adjacent the free edge of said closure flap and between the ends of the free edge of said closure flap.

3. A bag comprising a peripheral member and oppositely disposed circular members, said peripheral member being of non-self-sustaining fabric, one of said circular members being of non-self-sustaining fabric, a portion of said one circular member forming a closure flap to provide an opening to afford access within the bag, and having a free edge, means for closing said closure flap, stiffening means secured to said peripheral member, said stiffening means extending longitudinally of and within said peripheral member, said stiffening means further extending at a plurality of locations transversely to said longitudinal direction, and means for suspending the bag to hold said members in self-sustaining position, said suspending means

comprising an element secured to said closure flap and between the ends of the free edge of said closure flap of said one circular member.

4. A bag comprising a peripheral member 5 and oppositely disposed circular members, said peripheral member being of non-self-sustaining fabric, one of said circular members being of non-self-sustaining fabric, a portion of said one circular member forming 10 a closure flap to provide an opening to afford access within the bag, a series of fasteners for closing said closure flap, stiffening means for said peripheral member, said stiffening means being permanently secured to said peripheral 15 member, said stiffening means extending longitudinally of and transversely to the direction of length of said peripheral member, said stiffening means being disposed inwardly of said peripheral member and means for suspending the bag to hold 20 said members in distended position when said closure flap of said one circular member is in closed position, said suspending means including an element secured to said closure flap between the ends of 25 the free edge of said closure flap.

5. A bag comprising a peripheral member and oppositely disposed circular members, said peripheral member being of non-self-sustaining fabric, one of said circular members being of non-self-sustaining fabric, a portion of said one circular member forming 30 a closure flap to provide an opening to afford access within the bag, the free edge of said closure flap extending from one location adjacent 35 said peripheral member to another location adjacent said peripheral member, a series of fasteners secured to the free edge of said closure flap for closing said closure flap, stiffening means for said peripheral member, said stiffening means being permanently secured to and disposed within 40 said peripheral member, said stiffening means extending longitudinally of and at a plurality of locations transversely to the direction of 45 length of said peripheral member, and means for suspending the bag to hold said members in distended position when said one circular member is in closed position, said suspending means comprising an element secured to said closure flap of said one circular member adjacent the free edge of said closure flap.

6. A bag comprising a peripheral member and oppositely disposed circular members, said peripheral member being of non-self-sustaining fabric, one of said circular members being of non-self-sustaining fabric, a portion of said one circular member forming 55 a closure flap to provide an opening to afford access within the bag, the free edge of said closure flap extending from one location adjacent said peripheral member to another location adjacent said peripheral member, a series of fasteners secured to the free edge of said closure flap for closing said 60 closure flap, stiffening means for said peripheral member, said stiffening means being permanently secured to and disposed within said peripheral member, said stiffening means extending longitudinally of and at a plurality of locations transversely to the direction of 65 length of said peripheral member, and means for suspending the bag to hold said members in distended position when said one circular member is in closed position, said suspending means comprising an element secured to said closure flap of said one circular member adjacent the free edge of said closure flap.

70

7. A bag comprising a peripheral member and oppositely disposed side members, said peripheral member and said side members being of non-self-sustaining material, one of said side members being secured to one edge of said peripheral member and having a portion serving as a closure flap to provide an opening to afford access within the bag, fastener means for closing said closure flap, the other of said side members being secured to the opposite edge of said peripheral member, stiffening sheet material secured to said peripheral member serving to hold said peripheral member fully distended, and handle means for suspending the bag.

75

8. A bag comprising non-self-sustaining material serving as the material proper of the bag, said material including a peripherally extending portion, said material further including a side portion, peripherally disposed stiffening means for said peripherally extending portion and for maintaining the non-self-sustaining material of said one side taut, said material further including a portion for the side opposite said one side, said opposite side serving as the closure side of the bag to afford when open access to the interior of the bag, detachable means for closing said closure side, and handle means for suspending the bag.

80

9. A bag comprising a peripheral member and oppositely disposed side members, said peripheral member and said side members being of non-self-sustaining material, one of said side members being secured to one edge of said peripheral member and having a portion serving as a closure flap to provide an opening to afford access within the bag, fastener means for closing said closure flap, the other of said side members being secured to the opposite edge of said peripheral member, stiffening sheet material extending peripherally of said peripheral member and serving to hold said peripheral member at all times fully distended, the ends of said stiffening material being overlapped, and handle means for suspending the bag.

85

10. A bag comprising non-self-sustaining material, spaced stiffening members extending peripherally of the bag, said stiffening members being in the form of a band, each 90

105

110

115

120

125

130

band having disconnectible means for connecting its ends to one another.

11. A container formed of non-self-sustaining material and having a plurality of compartments, partition means defining said compartments and a stiffening member extending peripherally of said container, said stiffening member being in the form of a band.
- 10 12. A container formed of non-self-sustaining material and having a plurality of compartments, partition means defining said compartments and a stiffening member extending peripherally of said container, said stiffening member being in the form of a band, said band having open ends.
13. A container formed of non-self sustaining material and having a plurality of compartments, partition means defining said compartments and a stiffening member extending peripherally of said container, said stiffening member being in the form of a band, said band having open ends and disconnectible connecting means for the ends of said band.
14. A bag comprising non-self sustaining material, and having two compartments, a partition defining said compartments, spaced stiffening members extending peripherally of the bag, said stiffening members being in the form of a band, each band having disconnectible means for connecting its ends to one another, said stiffening means being disposed immediately adjacent said partition.
- 35 15. A multi-compartment bag of non-self-

sustaining fabric forming the bottom, sides and top of the bag, a stiffening member located in each compartment of the bag, a partition formed of fabric sewed at its periphery to the side portion of the first-named fabric, said bag being provided with suspending means and said stiffening members being of material to render the material of the bag self-sustaining and hold the several compartments in spaced relation when the bag is suspended.

16. A collapsible bag comprising fabric forming the bottom, sides and top of the bag and stiffening means extending peripherally of and secured to said fabric, said stiffening means being resilient to enable the bag to be twisted and folded after twisting and without rupture of said stiffening means, and means for enclosing the twisted and folded bag in collapsed position.

17. A multi-compartment collapsible bag of fabric forming the bottom, sides and top of the bag, a hoop located in each compartment of the bag, a partition formed of fabric sewed at its periphery to the side portion of the first-named fabric, said hoop or hoops being of material of sufficient resiliency to enable the bag to be vertically collapsed, then twisted and then folded without rupture of said hoops and means for enclosing the twisted and folded bag in collapsed position.

In testimony whereof I have signed this specification this 23rd day of November, 1921.

HELEN C. GAMBLE.
